UNITED STATES PATENT OFFICE

EMMETT H. TUTTLE, OF BERLIN HEIGHTS, OHIO

MUSIC CABINET AND STAND

Application filed January 15, 1930. Serial No. 421,015.

This invention relates to music cabinets and has for an object to provide a cabinet in which music books, manuscripts, as well as a musical instrument such as a violin may be conveniently stored and which may also be easily and quickly converted into a music rack for holding sheet music, instruction books, and the like.

A further object of the invention is to provide a novel music cabinet having an open top through which the musical instrument such as a violin and bow may be easily removed after the cover is raised, the cover when raised being adapted to be elevated considerably above the top of the cabinet and when in this position constituting a music rack.

A still further object is to provide a novel cabinet having an open top and music book racks on the sides, the top of the cabinet extending laterally and forming a closure for the book racks, such lateral extensions also having compartments therein for rosin and small articles such as strings and the like, which compartments as well as the open top of the cabinet are concealed when the cover of the cabinet is closed.

A still further object is to provide a cover for a cabinet such as above described, the cover having a ledge which is hinged to a vertically movable standard normally concealed within the cabinet, the hinge being of such novel construction as when open to position the cover sloped slightly backward beyond the vertical so as to position the sheet music or instruction books for convenient reading.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is a perspective view of a music cabinet embodying my improvements,

Figure 2 is a longitudinal sectional view

through the cabinet showing the cover dotted in open position,

Figure 3 is a view similar to Figure 2 showing the cover open and raised to constitute a music rack,

Figure 4 is a cross-sectional view on the line 4—4 of Figure 3, and

Figure 5 is a detail sectional view on the line 5—5 of Figure 3.

Referring now to the drawings in which like characters of reference designate similar parts in the various views, my improved music stand is shown to comprise a cabinet designated in general by the numeral 10, which is preferably supported upon legs 11 and comprises side walls 12 and 13, a rear wall 14, a bottom 15 and a front wall 16. The cabinet is open at the top and the front of the cabinet is provided at the bottom with a hinged door 17. A horizontal shelf 18 divides the cabinet into two compartments and access to the lower one may be obtained through the door 17 and access to the upper one through the open top of the cabinet. The shelf terminates short of the rear wall 14.

The cabinet is preferably formed of such dimensions as to house a violin 19 which may be placed upright on the shelf 18 and the latter is preferably padded as shown at 20 so as not to mar the finish of the instrument. The violin bow 21 is hung in the cabinet on a hook or nail 22, the cabinet being of sufficient height to receive the bow which as best shown in Figure 2 will project downwardly through the space between the rear wall 14 and shelf 18. The violin and bow may be inserted and removed conveniently through the top of the cabinet which as above stated is left open for this purpose.

Arranged on the sides of the cabinet are book racks for receiving instruction books and the like, each comprising a bottom 23, a top 24 which forms an extension of the top of the cabinet, and vertical strips 25 which connect the top and the bottom. The top 24 is provided with a plurality of pockets 26 into which may be placed small articles such as rosin, strings and the like.

The open top of the cabinet 10 and also the pockets 26 are closed by a cover 27. The cover

extends forwardly beyond the front of the cabinet to provide a projecting portion which may be grasped for raising the cover and also projects rearwardly beyond the rear wall of the cabinet. A strip 28 of wood or the like is secured to the underneath face of the cover at the rear edge thereof in any preferred manner and is centrally recessed as shown at 29 to receive a hinge 30. As best shown in Figures 2 and 3 the hinge is substantially U-shaped in contour, one leg of the hinge being equipped with an eye 31 through which a pin 32 is passed to secure the hinge to the transverse strip 28 as best shown in Figure 5. 15 A standard 33 is mounted to slide vertically in a recess 34 formed in the rear wall 14 of the cabinet. The standard is provided with a longitudinal slot 35. A bolt 36 is passed through an orifice in the rear wall 14 near the top thereof and is provided with a square neck 37 which fits in the slot 35 of the standard. The bolt is equipped with a wing nut 38 which may be tightened to hold the standard elevated at its upper limit of movement 20 as shown in Figure 3. 25

The hinge 30 is bolted as shown at 39 to the upper end of the standard. A plate 40 closes the recess 29 formed in the cross piece 28 and forms a stop against which the horizontal portion of the hinge bears as best shown in Figure 3. When the cover is rocked open, the stop 40 bears against the underneath face of the hinge 30 and maintains the cover sloped backwardly beyond the vertical, 30 in which position the cover forms a music rack for sheet music or instruction books which as will be understood will be placed upon the cross piece 28 or ledge and be supported by the cover at a convenient height 35 for easy reading. 40

In operation, assuming that it is desired to convert the cabinet into a music rack it is simply necessary to raise the lid to the position shown in dotted lines in Figure 2 and then elevate the standard 33 to any desired height where it may be locked in place by tightening the wing nut 38. 45

From the above description it will be seen that the violin and bow may be easily inserted or taken from the cabinet through the open top thereof when the cover is raised and that when the cover is lowered it forms a closure for the top of the cabinet and also forms a closure for the pockets 26. 50

It will be understood that the cabinet may be made of suitable interior dimensions to house a plurality of violins, or may be used to house musical instruments other than violins such for instance as cornets, clarinets, etc. 55

Having thus described the invention, I claim:

1. A music stand comprising a cabinet, a hinged top for the cabinet having a ledge at the rear edge, a vertically movable stand-

ard adjustably secured to the cabinet, and a hinge on said ledge securing said top to said standard and adapted when open to support the top sloping backward above the standard to form a music rack when the standard is raised. 70

2. A music stand comprising a cabinet having a compartment for housing a stringed instrument and open at the top, a cover forming a closure for said open top, a standard slidably secured to the rear wall of said cabinet and normally housed within the cabinet, said standard being slidable vertically above the cabinet, means for holding the standard in adjusted positions above the cabinet, a hinge securing said cover to the upper end of the standard and adapted to hold said cover sloping backward above said cabinet to form a music rack, and a stop for limiting opening movement of said hinge. 80 85

3. A music stand comprising a cabinet having a vertical guide slot in the inner face of the back and having an open top, a cover for the open top, a standard mounted to slide vertically in said slot, means for securing said standard in various adjusted positions in said slot, and a cover hinged to the upper end of the standard and adapted to form a closure for the open top of the cabinet when said standard is disposed at its lower limit of movement, said cover being adapted to be rocked open to form a music rack disposed above the cabinet when said standard is disposed at its upper limit of movement. 90 95

4. A music stand comprising a cabinet open at the top to receive a stringed instrument through the open top for housing the same, a standard adjustably mounted to be held at various heights on the cabinet, a cover for the cabinet hinged to the top of the standard and having a music supporting ledge, said ledge having a recess, a stop bridging the recess, a pin in the recess, and a U-shaped hinge secured to the top of the standard and pivotally engaging said pin to hinge the cover to the standard, said hinge engaging said stop when the cover is open and the standard is raised to hold the cover sloping backward beyond the vertical to form a music rack. 100 105 110 115

In testimony whereof I affix my signature.

EMMETT H. TUTTLE. [L. S.]
